UNITED STATES PATENT OFFICE.

ERASTUS S. FRENCH, OF PRINCETON, ASSIGNOR TO GILMAN WAITE, OF BALDWINSVILLE, MASSACHUSETTS.

CONVERTIBLE CHAIR.

SPECIFICATION forming part of Letters Patent No. 445,774, dated February 3, 1891.

Application filed February 12, 1890. Serial No. 340,199. (No model.)

To all whom it may concern:

Be it known that I, ERASTUS S. FRENCH, of Princeton, in the county of Worcester and State of Massachusetts, have invented a new and useful Improvement in Convertible Chairs, of which the following is a specification, reference being had to the accompanying drawings, in which—

Figure 1 is a front and Fig. 2 a side elevation of my new chair, the chair in each view being shown in its elevated position. Fig. 3 is a plan of the chair shown in Figs. 1 and 2, the chair being in its lower position for use as a low chair or carriage. Fig. 4 is a section 15 on line 44 of Fig. 3.

My invention is a convertible chair made up of a main or supporting frame and two seats, one seat being for use when the chair is used as a high chair and the other seat being for use when the chair is used as a low chair or carriage.

In the drawings, which show my invention embodied in one form of chair, the best form now known to me, A is the supporting-frame; 25 a, the high-chair seat; a', a back for seat a; a², the low-chair seat; a³, a back therefor, and a⁴ the handle. In this form of my new chair the back a' is hinged to supporting-frame A and is locked in position for use as a back for 30 the high chair (see Fig. 2) by the handle a⁴ and a hook a⁵. When the chair is to be used as a low chair, frame A is turned in the usual way, thereby bringing the seat a², which is nearly at right angles to high-chair seat a, 35 and mounted in the frame A at some distance from high-chair seat a, into position for use. (See Figs. 3 and 4.) The back a' may, if desired, be turned on its hinges, so as to rest on the legs a⁶ of frame A. In this position the back a' serves not only as a guard to hold 40 a child in place on the low seat a², back a' being fastened by a hook a⁷ to legs a⁶, but also as a play-table. This combination of frame A, provided with a seat with a back which is

adapted to form a play-table, is also a feature 45 of my invention. The frame A is provided with a foot-rest a⁸ for use when seat a is used, and this foot-rest is so mounted as to be readily turned out of the way when the low chair or carriage is used. When the foot-rest is in 50 use, it rests on stops a⁹ and projects beyond frame A in the usual manner. When the chair is used as a low chair, rest a⁸ is turned within frame A against stops a⁹, as will be readily understood by all skilled in the art 55 without further description.

The main advantage of my new chair is the ease with which it may be converted and the safety which it possesses as a high chair.

I am aware of United States Patents No. 60 206,602, to Nichols, dated July 30, 1878, and No. 198,491, to Freshman, dated December 25, 1877, and also English Patent No. 3,938 of 1888, and disclaim all that is shown in them.

What I claim is—

1. In a convertible chair, frame A, provided with a seat a and its back a' and a seat a² and its back a³, the seat a and its back a' being at one end of frame A to serve as a high-chair seat and back, and seat a² and its back 70 a³ being at the other end of frame A to serve as a low-chair seat and back, seat a and its back a' being independent of and at a distance from seat a², and its back a³ and seat a uniting the main pieces of frame A, all substantially as and for the purpose set forth. 75

2. In a convertible chair, the combination of a supporting-frame A, two seats a a² supported thereby, one seat being at an angle to the other, and a movable back a' for seat a, 80 movable back a' swinging from its position as a back for seat a into position to serve as a guard for seat a², and vice versa, substantially as and for the purpose set forth.

ERASTUS S. FRENCH.
